UNITED STATES PATENT OFFICE.

EDWARD F. CALDWELL, OF NEW YORK, N. Y., ASSIGNOR TO THE PHOENIX GLASS COMPANY, OF PITTSBURG, PENNSYLVANIA.

DESIGN FOR A GLOBE OR SHADE.

SPECIFICATION forming part of Design No. 26,646, dated February 16, 1897.

Application filed January 13, 1897. Serial No. 619,129. Term of patent 7 years.

To all whom it may concern:

Be it known that I, EDWARD F. CALDWELL, a citizen of the United States, residing at New York, in the county of New York and State of New York, have invented a certain new and useful Design for a Globe or Shade; and I do hereby declare the following to be a full, clear, and exact description of the invention, such as will enable others skilled in the art to which it appertains to make and use the same.

My invention has relation to designs for gas, electric, and lamp globes and shades; and it consists in the shape and configuration herein described and illustrated.

In the accompanying drawings, Figure 1 is a plan view, and Figs. 2 and 3 are side views, of a globe embodying my design.

The shape of the body of the globe in ver-

tical section is that of a tulip flower, but is provided with flattened panels *a a*, extending from the mouth to near the neck-opening and may be appropriately etched. In horizontal section the globe is octagonal.

The upper edge of the globe is scalloped, each panel being concave at its upper end, as shown.

What I claim as new is—

The design for a globe or shade as described and shown.

In testimony whereof I have affixed my signature in presence of two witnesses.

EDWD. F. CALDWELL.
